UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 16, 1920. Serial No. 431,198.

To all whom it may concern:

Be it known that I, WALTER P. ALBERT, a citizen of the United States, residing at East Orange, in the county of Essex, State 5 of New Jersey, have invented certain new and useful Improvements in Telephone Systems, of which the following is a full, clear, concise, and exact description.

This invention relates to telephone exchange systems and particularly to systems 10 of the semi-automatic type, involving the services of operators as well as automatic switches for completing talking connections.

In certain semi-automatic systems the 15 subscribers' lines are terminated in calling jacks at operators' positions in the central office. So far as the subscriber is concerned his line is identical in all respects to an ordinary manual line. To make a call he removes his receiver from its switch-hook and 20 communicates the wanted number to the responding operator. At the central office, too, the duties of the operator correspond in some respects to those of the usual manual operator. She answers the calling line by inserting the plug of an idle cord circuit at her position in the jack of the calling line. On receiving the number of the 25 desired line from the calling party she then proceeds to record the same on a set of keys, which determine the operation of a register controlling mechanism to govern the selective 30 operation of automatic switches in the extension of the call. In order that the operator may be relieved of the manipulation 35 of keys, each time a call is answered, for connecting her telephone set to the calling line and disconnecting it therefrom certain instrumentalities are used to accomplish the 40 same automatically.

The object of the present invention is the provision, in a system of the above described character, of an arrangement for automatically connecting the operator's set to the 45 calling line and disconnecting the same therefrom, wherein a connecting relay acts in response to certain operations to complete a talking connection between the operator's set and the calling line and thereafter acts 50 to sever said connection responsive to the register mechanism when such mechanism has reached a certain stage in its operation.

A feature of the invention relates to the provision of a relay which acts when the 55 operator responds to the call to connect the

calling line to the operator's set and later acts in response to the register mechanism when such mechanism has completed its control of the automatic switches, to disconnect the calling line from the operator's set 60 and to extend such line through to said automatic switches.

Other features of the invention will become more apparent from a consideration of the following detailed description and the 65 appended claims.

In the accompanying drawing, which constitutes a part of this application, Figs. 1 to 5 inclusive, when arranged in the order shown in Fig. 6, illustrate a telephone exchange system in which the features of the present invention are incorporated. Fig. 1 shows a subscriber's telephone line terminating in an answering jack before an operator's position in the central office. This figure also shows an operator's cord circuit provided with an answering plug and means for associating the operator's telephone set with the cord circuit. 70

Fig. 2 shows one of a plurality of cord 80 finder switches having access to the several cords at the operator's position and serving to associate an idle register sender with a desired one of said cord circuits.

Fig. 3 illustrates the keyboard at the operator's position consisting of a plurality of rows of office and numerical keys upon which the designations of called lines are recorded. Also this figure shows in detail the registers and sender individual to the 85 cord finder in Fig. 2, the function of which is to register the designation set up on the operator's keyboard to determine the selective operation of the switches in the extension of the connection. 90

In Fig. 4 there is shown to the left two automatic switches, namely, a district switch and an office switch. The district switch shown at the extreme left of the figure is individual and is connected directly to one 100 of the cord circuits at the operator's position. At the right of the figure is shown an incoming switch to which connections are extended from the office selector. 95

Fig. 5 shows a second group selector in 105 the same office and a final selector for completing the connection to called subscribers' lines in such office.

The selector switches shown in Figs. 4 and 5 are of the step - by - step two movement 110

type arranged to be operated by stepping magnets first in a group selecting movement and next in an automatic trunk hunting movement. The final selector or connector switch shown in Fig. 5 differs from the preceding switches in that both its primary and secondary operations are directive movements effected by the last two series of impulses.

- 10 The cord finder switch, the several elements of which are located within the broken rectangle at the upper left-hand corner of Fig. 2, consists of an ordinary single movement rotary step-by-step switch. 15 This switch is provided with several brushes 202, 203, 204, etc., which are driven over corresponding arcuate rows of terminals by a stepping magnet 200. The several terminals of the contact banks of the cord finder 20 switch are each individual to a cord circuit at the operator's position. The function of the cord finder switch is to search for and find the particular operator's cord circuit that has been taken for use in responding 25 to a calling line.

The operator's keyboard shown in Fig. 3, one of which is provided for each operator's position, consists of four rows of office keys 300, 305, 310, and 315, and four rows 30 of numerical keys 320, 325, 330, and 335, and also a set of station keys 340. In common to the operator's keyboard there is provided a plurality of register senders. Each 35 of these register senders comprises four office registers generally designated as 302, 307, 312, and 317, and four numerical registers 322, 327, 332, and 337, and also a station register 342. These registers comprise a small rotary step-by-step switch having 40 two movable brushes and a stepping magnet for driving said brushes over their respective rows of terminals. The brushes and the terminal blanks and the stepping magnets together with certain control elements are, in the case of each of the several registers, shown as confined within the 45 space of the respective broken rectangles in Fig. 3.

For controlling the various operations of the registers a sender control switch is provided. This switch is of the step-by-step type consisting of a stepping magnet 372 and a plurality of contact elements operated by said magnet. The step-by-step contact 55 elements of the sender control switch are located in various places throughout Fig. 3 of the drawing and their closing positions are illustrated by means of ordinals adjacent to said contacts. In addition to the 60 registers and sender control switch there is provided a time measure switch generally designated at 240. The purpose of this switch is to govern the advance of the sender control switch from one position to 65 another and to postpone the time at which

the succeeding registers of the sender are rendered effective for a purpose more clearly to be set forth hereinafter.

Inasmuch as the register sender must be adapted to control varying kinds of connections depending upon the nature of the office to which the call is being made, and also the character of the switching apparatus with which such office may be equipped, it is necessary to make provision in the sender for taking care of these varying conditions. To this end a class switch is utilized and operates in accordance to the position to which it is adjusted to influence the operation of the sender control switch during the time 70 the register sender is exercising its control over the selective switches. The class switch consists of a plurality of step-by-step elements arranged to be moved from position to position by stepping magnet 214. 75 The several switching elements governed by the magnet 214 are located within the area set off by the broken line at the right of Fig. 2 and their closing positions are designated by the adjacent ordinals. 80

A complete register controlling mechanism consists of a cord finder switch, a set of office and numerical registers, a time measuring switch and the associated circuits and other controlling elements. There 85 may be several of these register controlling mechanisms to serve an operator's position. Consequently, an allotter switch is used for assigning an idle register sender for use so that only one such sender will be appropriated and associated with the cord circuit 90 when the operator responds to a calling line. The allotter switch used for this purpose is a step-by-step switch consisting of a stepping magnet 210 and a plurality of switching elements driven by said magnet through their successive closing positions. These 95 elements are shown at 209, 211, 212, and 213. In the specific embodiment illustrated, the allotter switch 210 serves to allot three 100 different register senders for use by the operator. The register sender shown in detail in the drawing is assigned for use when the allotter switch is in position 1, while 105 the other two senders (not shown) are assigned respectively in positions 5 and 9 of the allotter. Further explanation of the 110 functions of the allotter switch will be taken up hereinafter.

It is believed that a clearer understanding 115 may be had of the principles of this invention by giving a detailed description of the operation of the system in the establishment of a call from one subscriber's line to another. To this end it is assumed that the 120 subscriber, whose telephone line 100 terminates before an operator's position in the office, wishes to obtain a connection with a subscriber's line, such as line 540, belonging 125 to the same office. The subscriber at sub- 130

- station 100, on removing his receiver from the switch hook, closes a circuit from battery through the left-hand winding of line relay 101, contact and outer left-hand armature of relay 102, over the loop of substation 100, inner left-hand armature and contact of relay 102, right-hand winding of relay 101 to ground. The line relay 101 becomes energized and closes a circuit to cause the illumination of the individual line lamp 103 at the operator's position. The operator observing the lamp 103 burning knows that the subscriber of the line to which such lamp is individual wishes to make a call. She thereupon seizes the plug 105 of one of her idle cord circuits and inserts it in the answering jack 104 of the calling line. The insertion of plug 105 in jack 104 forces the spring 136 into engagement with its contact and thereby completes a circuit for the cut-off relay 102. Relay 102 opens the circuit of the line relay 101 and extinguishes the calling lamp 103. Relay 102 also establishes a circuit from battery through the winding of relay 106, sleeve of plug 105, sleeve of jack 104, right-hand armature and contact of relay 102 to ground. Relay 106 attracts its armatures and completes a circuit from battery through the calling line supervisory lamp 108, resistance 137, left-hand armature and contacts of relay 106 to ground. The lamp 108, however, is shunted out at this time by reason of the fact that the supervisory relay 129 is energized in series with the calling subscriber's line, the current for relay 129 being supplied through the left-hand windings of repeating coil 139. The shunt circuit around the lamp 108 may be traced from battery through the armature and contact of relay 129, resistance 138, resistance 137, left-hand armature and contact of relay 106 to ground. Therefore, the calling supervisory lamp 108 remains extinguished.
- As soon as relay 106 energizes when the plug is inserted in the jack, a circuit is completed from battery through the winding of relay 109, back contact and middle armature of relay 107, front contact and outer right-hand armature of relay 106, contact and armature of relay 117 to ground. In parallel to this circuit a circuit is also completed from battery through the winding of relay 110, and thence to ground at the contact and armature of relay 117. It will be noted that relay 118 is also included in series with the parallel circuits for relays 109 and 110. Relay 118, however, does not energize since it is shunted out by the direct circuit to ground at the contact and armature of relay 117. Relays 109 and 110 immediately lock up independently of the armatures and contacts of relays 103 and 107 by means of the following circuit: battery, through the windings of relays 109 and 110 in parallel, front contact and inner left-hand armature of relay 110, key 119, armature and contact of relay 118 to ground. Relay 109, on attracting its armatures, establishes a conversational circuit between the operator's telephone set 130 and the calling line 100. Battery current is fed to the calling subscriber's line over the following circuit: battery, through the lower left-hand winding of repeating coil 139, winding of relay 129, front contact and inner lower armature of relay 109, lower normal contacts of the keys 135, 134, 133, and 132 in series, contact and lowermost armature of relay 109, ring of plug 105, ring of jack 104, thence through the loop of the calling subscriber's line 100 and returning by way of tip of jack 104, tip of plug 105, uppermost armature and contact of relay 109, through the upper normal contacts of keys 132, 133, 134, and 135 in series, inner upper armature and front contact of relay 109, through the upper left-hand winding of repeating coil 139 to ground. It will also be noted that the operator's telephone set 130 is connected in parallel to the circuit traced and thereby receives talking current through the left-hand windings of the repeating coil 139.
- When relay 110 becomes energized, a circuit is completed from battery through the windings of relays 113 and 114 in parallel to ground at the contact and left-hand armature of relay 110. Relay 114 closes a circuit from battery through the winding of relay 117 to ground at its left-hand armature and contact. Relay 117 attracts its armature and removes the shunt from around the winding of relay 118. Relay 118, however, cannot energize at this time since the current supply through the windings of relays 109 and 110 in parallel is now shunted away from relay 118 over the circuit leading through the key 119 and armature and contact of relay 118. Relay 114 also completes a circuit from ground through the interrupter 121, front contact and inner right-hand armature of relay 114, contact and outer right-hand armature of relay 116, resistance 126, lamp 123 to battery and ground. The lamp 123 is intermittently illuminated and extinguished and serves to indicate to the operator that a register sender mechanism is about to be associated with the cord circuit she has taken for use. The lamp 123 will continue to flash until the associated sender has completed its function of controlling the selective switches and is disassociated from the cord circuit.
- The relay 113, which energizes in parallel with relay 114, operates to initiate the movement of the allotted cord finder to hunt for the calling cord circuit. The start circuit for setting the cord finder in operation may be traced from ground through the contact and left-hand armature of re-

4

lay 112, inner right-hand armature and contact of relay 106, innermost armature and back contact of relay 107, outer left-hand armature and contact of relay 113, conductor 241, contact 212 of the allotter switch closed in position 1, conductor 242, lower left-hand contact 373 (1) of the sender control switch, contact and armature and winding of the stepping magnet 372 to battery and ground. Magnet 372 becomes energized, interrupts its own circuit and again becomes deenergized. The construction of the sender control switch is such that the several contact elements are advanced from one position to another on deenergization of the stepping magnet 372. It may be well to observe at this point that the stepping switches which comprise the several registers shown in the drawing, and also the stepping switch used as a time measure device, shown at 240, are also designed to advance their brushes upon deenergization of the respective stepping magnets. Consequently, upon the first deenergization of the stepping magnet 372, the sender control switch is advanced out of position 1 and into position 2. In this position the cord finder is started in operation by means of a circuit closed from battery through the winding and armature and contact of the stepping-magnet 200, conductor 225, lower left-hand contact 364 (2) to ground. The stepping magnet 200 interrupts its own circuit and advances the brushes 202, 203, 204, 205, and 206 from position to position searching for the set of terminals individual to the cord circuit shown in Fig. 1. As soon as the test brush 203 of the cord finder reaches the terminal identifying the calling cord, a circuit is established from battery through the winding of magnet 200, winding of relay 201, conductor 229, left hand contact 365 (2), conductor 228, brush 203, contact and inner left-hand armature of relay 113, back contact and outermost armature of relay 107 to ground. The stepping magnet 200 and relay 201 have become permanently energized in this circuit and the brushes of the cord finder are brought to rest upon the terminals individual to the operator's cord circuit for which it was searching. The relay 201, on energizing, completes a circuit from ground through its armature and contact, conductor 231, upper left-hand contact 373 (2), contact and armature and winding of the stepping magnet 372 to battery and ground. Magnet 372 energizes, interrupts its own circuit and deenergizes to advance the contacts of the sender control switch to their next position, 3. As the sender control switch leaves position 2 it opens at the left-hand contact 365 the original energizing circuit for magnet 200 and relay 201. The magnet 200 and relay 201 are main-

tained energized by means of a circuit closed through the right-hand contact 365, conductor 227, brush 204, conductor 243, contact and outermost right-hand armature of relay 114, contact and outer right-hand armature of relay 112, winding of relay 127 to ground. 70

Relay 127 becomes energized in series with magnet 200 and relay 201 and closes a circuit from ground through its outer right-hand armature and contact, winding of relay 111 to battery and ground. Relay 111 locks in a circuit from battery through its winding and contact and inner right-hand armature to ground at the inner right-hand armature of relay 113. Relay 111 also closes a circuit from battery through the winding of relay 107 to ground at the contact and outer left-hand armature of relay 111. Relay 107 locks up in a circuit from battery through its winding and front contact and innermost armature, contact and inner right-hand armature of relay 106 to ground at the left-hand armature and back contact of relay 112. 80 90

As has been seen from the above description, the operator's telephone set 130 is associated by means of relay 109 with the calling subscriber's line, and an idle sender mechanism associated with the particular cord circuit utilized by the operator, both of which operations are responsive automatically to the insertion of the plug of the cord circuit in the jack of the calling line. The operator now challenges the calling line and requests the information concerning the connection desired. The calling subscriber orally communicates to the operator the name of the office and also the number of the called line in the office with which he wishes a telephone connection. Before proceeding with the duties of the operator in recording on the keyboard, the designation communicated to her, a preliminary explanation will be given with regard to the various functions of the keys shown at the operator's position. 100 105 110

As hereinbefore noted the operator's keyboard consists of two main parts. The first part comprises four rows of keys 300, 305, 310, and 315, which are used exclusively for designations pertaining to the selection of offices and the routing of calls. In a large system, especially where many offices are concerned, the central office senders must be adapted to control the local switches in the office to select outgoing trunks leading to the several distant offices in the area, as well as trunks leading to switches having access to local lines. The local selections, 115 120 125 namely those taking place at the office of which the calling line appears, are generally taken care of by two selector switches, the district selector and the office selector. These switches in the present disclosure are shown 130

in the left-hand portion of Fig. 4. In accordance with the particular type of office keyboard illustrated herein, the majority of the outlying offices in the area will be identified by a code number consisting, for example, of three characters. When a subscriber requests a connection to any one of these offices the operator, knowing the corresponding code, will depress the necessary combination of three office keys, one located in each of the three rows 305, 310, and 315. By any suitable scheme of wiring the particular combination of keys operated will cause the positioning of all or as many as necessary of the office registers, which ultimately determine the selection of a trunk leading to the outlying office represented by said code. While many of the offices in the system will be identified by codes represented by the three rows of office keys mentioned, certain offices will have a single individual key at the operator's keyboard. Such offices are those to which the traffic is particularly heavy, and in order to obviate the necessity of depressing a plurality of keys for every call the operator is provided with a row of keys 300, each of which identifies one of these offices.

The second part of the operator's keyboard consists of four rows of numerical keys 320, 325, 330, and 335, and a row of stations keys 340. On these keys the operator may record the numerical designation of the called subscriber's line and also identity of the station in case of a party line. As will be taken up in detail later on, the record produced by the numerical keys determines the selection of the called line in the particular office to which the connection is extended in accordance with the designation set up on the office keyboard.

Returning now to the point where the calling subscriber communicates the desired designation to the central office, the operator upon receiving this information proceeds to make a record thereof on the office and numerical keys at her position. It will be assumed that the called subscriber's line in the present case terminates in the same office to which the calling subscriber's line belongs and in which the operator's position is located. This being the case the district and office switches shown at the left of Fig. 4 should be operated to select a trunk routing the connection to the local switches shown at the right of Fig. 4 and in Fig. 5 for completing the connection to the called subscriber's line. Should connection be desired with a distant office it will be seen that the district and office switches are then operated to select an outgoing trunk leading to such office. In the present case the key 371 in the row 300 has been assigned for controlling the district and office switches to make local connections. As above ex-

plained, the remaining office keys in this row may serve to determine the selection of inter office trunks leading to the several offices to which said keys are individual. Furthermore, it will be considered that the called line is an ordinary line having the numerical designation 8681. Accordingly, the operator depresses the office key 371, the numerical keys 393, 394, 395, and 398, and the no stations key 396.

Inasmuch as the particular connection being considered is one of the type in which only the local district and office selectors need be operated to select a trunk leading to the local group selectors, only the last two of the office registers 312 and 317 are needed. Therefore, the depression of the office key 371 will be effective in setting only these two registers of the office group together with the class switch shown to the right of Fig. 2.

The circuits for causing the setting of these registers may be traced from battery through the windings and armatures and contacts of the stepping magnets 311 and 316 of registers 312 and 317, and from battery through the winding and armature and contact of the stepping magnet 214 of the class switch, thence by way of the common conductor 233, lower contact 213 (1) of the allotter switch, the upper spring of the row contact 367 to ground. The contact 367 is common to all of the keys of the row 300 and is arranged to be closed when any one of said keys is depressed. In the parallel circuit above traced, the stepping magnets 311, 316, and 214 are repeatedly operated to advance the registers 312, 317 and the class switch to search for their respective positions, as determined by the depressed office key 371. In order that the first two registers 302 and 307 may not be operated in parallel with other registers, circuits are completed for maintaining their stepping magnets permanently energized.

The circuit for magnet 301 extends from battery through the winding of said magnet relay 303, contacts 378, brush 329 and its normal position terminal, lower springs of contact 367 to ground. Similarly a circuit is completed from battery through the winding of stepping magnet 306, winding of relay 304, contact 379, brush 334 and its first position contact, lower springs of contact 367 to ground. The stepping magnet 311 of register 312 continues to operate until the brush 339 encounters the terminal 368. At this time a circuit is completed from battery through the winding of magnet 311, winding of relay 308, contacts 380, brush 339, terminal 368, inner left-hand contact of key 371 to ground. The magnet 311 becomes permanently energized in this circuit and the brushes 339 and 338 are brought to rest. Likewise, the stepping magnet 316 continues to operate until the brush 334 engages its terminal 369, at

which time a circuit is completed from battery through the winding of magnet 316, winding of relay 309, contacts 381, brush 344, terminal 369, right-hand contact of key 371 to ground. The brushes 344 and 343 are thereby stopped. The class switch will continue to operate until it reaches a position representing the particular class of connections to which the one being considered belongs. Assume that position 4 of the class switch is the position assigned for this particular class of calls. Hence, when the class switch reaches position 4 it is brought to rest by means of a circuit from battery through the winding of stepping magnet 214, winding of relay 215, contacts 363 (3), lower left-hand contact 219 (4), outer left-hand contact of key 371 to ground.

The numerical registers 322, 327, 332, 337 and the stations register 342 are positioned in a similar manner in response to the depression of the numerical and stations key. The circuits for stepping magnets 321, 326, 331, 336 and 341 extend from battery through the windings and armatures and contacts of these magnets in parallel, contacts 392, right-hand contact of key 396 to ground. The registers commence to rotate step-by-step in search of the positions determined by the depressed keys. The first register 322 stops when its brush 346 reaches the terminal connected to the left-hand contact of key 393, the second register 327 stops when its brush 348 reaches the terminal connected to the left-hand contact of relay 394, the register 332 stops when its brush 350 engages the terminal connected to the key 395, register 337 stops when its brush 352 reaches terminal connected to key 385, and the stations register 342 makes a complete revolution and comes to rest in its normal position, at which time brush 353 is making contact with the terminal connected to the no stations key 396. The stop circuits of the several registers include the windings of relays 313, 314, 318, 319, and 323, and the sender control switch contacts 387, 388, 389, 390, and 391, respectively.

As soon as the office registers 312 and 317 and the class switch have been positioned, a circuit is closed as follows for driving the sender control switch out of position 3 and into position 4: battery, through the winding and armature and contact of stepping magnet 372, lower left-hand contact 382 (3), right-hand armatures and contacts of relays 309 and 308 in series, contacts 216 (4), contact and right-hand armature of relay 215 to ground. Where the first two registers of the office group 302 and 307 are not to be utilized in the establishment, it becomes necessary for the sender control switch to skip the positions assigned to these registers. This is accomplished by the class switch which is now standing in

position 4. The circuit for driving the sender control switch through positions 4 and 5 may be traced from battery through the winding and armature and contact of stepping magnet 372, contact 366 (4+5), contact 218 (4) to ground. The sender control switch is thus driven into position 6 where it renders the register 312 effective to control the transmission of the first series of impulses to the district selector switch. The register sender is now in condition to transmit the first series of impulses to cause the group selection at the district switch, depending upon the position taken by the register 312, responsive to the depressed office key 371.

The impulse circuit over which series of impulses are transmitted from the register sender to the stepping magnets of the several selector switches was completed at the time the relay 127 became energized. This circuit may be traced from battery, through the right-hand winding of the relay 404 at the district selector, back contact and inner left-hand armature of relay 412, conductor 401, inner left-hand armature and front contact of relay 127, conductor 245, brush 206, armature and contact of stepping relay 207, brush 205, conductor 244, front contact and outer left-hand armature of relay 127, conductor 400, outer left-hand armature and back contact of relay 412, left-hand winding of relay 404 to ground. The relay 404 becomes energized and completes a circuit from battery through the winding of slow-to-release relay 405, front contact and armature of relay 404 to ground at the contact and outer right-hand armature of relay 412. Provided the time measuring switch 240 is in its normal position as shown in the drawing at the time when the sender control switch reaches position 6, or as soon thereafter as said time switch reaches its normal position, a circuit is closed as follows: battery, through the winding of relay 252, normal contact 248, brush 247, conductor 237, lower right-hand contact 377 (6), brush 338 to ground. Relay 252 becomes energized and completes a circuit from battery through the winding of the time measuring switch stepping magnet 246, the inner armature and front contact of relay 252 to ground. The stepping magnet 246 is thus locked in an energizing circuit and prevented from advancing the brush 247. Relay 252 also completes a circuit from ground through its contact and outer armature, conductor 235, through the winding of stepping magnet 372 to battery and ground. Magnet 372 becomes energized preparatory to advancing the contacts of the sender control switch to its next position when its circuit is opened. The next time the constantly rotating interrupter 376 is closed a circuit is completed from ground through

said interrupter, contact 375 (3+15), conductor 234, winding of relay 249 to battery and ground. Relay 249 becomes energized and a circuit is established from battery 5 through the winding of relay 251, outer left-hand armature and contact of relay 249, back contact and left-hand armature of relay 250, contact 248, brush 247, conductor 237, lower right-hand contact 377 (6), to ground through brush 338. Relay 251 completes a circuit from battery through its winding and contact and armature and the winding of relay 250 to the grounded conductor 237. Relay 250, however, does not 10 energize at this time since its winding is shunted out by the direct circuit to ground closed through the outer left-hand armature and contact of relay 249. On the next opening of interrupter 376 and the result- 15 20 ant deenergization of relay 249, relay 250 energizes and lock up in series with relay 251.

On the next closure of the interrupter 376, relay 249 becomes energized and completes a circuit from battery through the winding of register stepping magnet 311, upper right-hand contact 374 (6), conductor 236, inner right-hand armature and front contact of relay 249, contact and right-hand 25 30 armature of relay 250, brush 247 to the grounded conductor 237. Magnet 311 becomes energized preparatory to advancing the brushes 339 and 338 forward to their next position when its energizing circuit is severed. Relay 249 also completes a circuit from battery through the winding of the stepping relay 207, inner left-hand armature and contact of relay 249, front contact and left-hand armature of relay 250, brush 249 35 40 to the grounded conductor 237. Relay 207 becomes energized and opens the impulse circuit leading to the district selector switch. Relay 404 consequently becomes deenergized and closes a circuit for ground through the outer right-hand armature and back contact of relay 412, armature and back contact of relay 404, armature and front contact of relay 405, winding of slow-to-release relay 406, winding of the primary stepping magnet 407 45 50 to battery and ground. Stepping magnet 407 energizes and advances the brushes 413, 414, and 415 to the first level of terminals. Relay 406, which also energizes, completes a circuit as follows as soon as the 55 60 brush shaft has taken its first step to close the off normal contacts 411: battery, through the winding of relay 410, lowermost springs of contact 411, armature and front contact of relay 406, conductor 402, back contact and inner right-hand armature of relay 112, front contact and outermost armature of relay 107 to ground. Relay 410 locks up in a circuit from battery through the winding of said relay, lowermost springs of contact 411, armature and contact of the secondary step- 65 70 75 80 85 90 95 100 105 110 115 120 125 130

ping magnet 409, contact and outer armature of relay 410 to ground at the contact and outer right-hand armature of relay 412. When the interrupter 376 again opens, relay 249 deenergizes and breaks the above traced circuits of stepping magnet 311 and stepping magnet 207. The magnet 311 deenergizes and advances brushes 339 and 338 forward one step. Relay 207 also deenergizes and completes the circuit of the relay 404. Relay 404 attracts its armature and opens the circuit of relay 406 and stepping magnet 407. Magnet 407 becomes deenergized but the slow-to-release relays 405 and 406 maintain their armatures attracted during the series of impulses. For each succeeding closure and opening of the interrupter 376, the register brushes 339 and 338 are moved forward one step and an impulse is sent to the district switch to operate the primary stepping magnet 407. When the requisite number of impulses have been sent, the register 312 reaches its normal position and brush 338 engages a non-grounded terminal. At this time the above traced circuits for relays 252, 251, and 250 are opened and these relays become deenergized. Relay 252 opens the circuit of the stepping magnet 246 which deenergizes and advances the time measuring switch out of its normal position. Hereafter each time the interrupter 376 closes and relay 249 attracts its armatures, a circuit is completed from battery through the winding of magnet 246, inner armature and back contact of relay 252, contact and outer right-hand armature of relay 249 to ground. Under the control of relay 249 the time measuring switch makes a complete revolution. The period required for this switch to again reach its normal position is so taken as to insure a time interval great enough for the selector switches to make a maximum trunk hunting movement. Relay 252, on deenergizing, also opens the circuit of the stepping magnet 372, which becomes deenergized and advances the sender control switch out of position 6 and into position 7. Since the relay 250 is now deenergized while the time measuring switch is running through its cycle, the relay 207, and, consequently, the relay 404 remain energized and unaffected by the intermittent operation of relay 249. 105 110 115 120 125

On the lapse of the necessary interval, following the transmission of the series of impulses, the slow-to-release relay 406 becomes deenergized and a circuit is closed from battery through the inner armature and contact of relay 410, winding of the secondary stepping magnet 409, normal contacts of relay 406 to the grounded conductor 402. Magnet 409 energizes and advances the brushes of the selector switch onto the first set of terminals in the selected level. The energization of the stepping magnet 409 opens the holding circuit of re-

lay 410, which becomes deenergized and in turn severs the operating circuit of said stepping magnet. Stepping magnet 409 therefore releases its armature. In case the 5 first trunk, upon the terminals of which the brushes 413, 414, and 415 are now standing, is busy, a ground potential will exist on the test terminal 418 thereof. Relay 410 therefore becomes energized as soon as the stepping magnet 409 deenergizes in a circuit from battery through the winding of said relay, lowermost springs of contact 411, armature and contact of magnet 409, back contact and inner right-hand armature of relay 412, brush 415 to the grounded test terminal 418. It will be noted that a parallel circuit is completed through the winding of relay 412 to the grounded conductor 402. Relay 412, however, remains inert since 10 it is shunted out directly by the busy ground potential on test terminals 418. Relay 410 again closes the circuit of stepping magnet 409 which operates to advance brushes to the next set of terminals. When the test 15 brush 415 reaches the test terminal 418 of the first idle trunk, relay 412 is included in series with relay 410. Relay 412 thereupon attracts its armatures but due to its comparatively high resistance, relay 410 cannot energize. The stepping magnet 409 ceases 20 to operate and the brushes are brought to rest in engagement with the terminals of the idle trunk. The operation of relay 412 opens the circuit of relay 404 which becomes 25 deenergized and in turn opens the energizing circuit of relay 405. Relay 412 also extends the grounded conductor 402 by way of the front contact and inner right-hand armature of said relay through to the test terminal 418 to render the selected trunk busy to other district switches.

As soon as the time measuring switch 240 reaches its normal position terminal 248, the 45 circuit of relay 252 is closed by way of the conductor 237, lower left-hand contact 377 (7), brush 343 of register 317 to ground. Relay 252 closes a holding circuit for the stepping magnet 246 and also a holding circuit for the stepping magnet 372 of the 50 sender control switch. The next time relay 249 becomes energized, relay 251 is operated in the circuit above traced to terminal 248, brush 247, and thence to ground over conductor 237. Relay 251 prepares 55 a circuit for relay 250 which becomes energized and locked up as soon as relay 249 releases its armatures. The next closure of interrupter 376 and the 60 resultant energization of relay 249 establishes a circuit from battery through the winding of the register stepping magnet 316, upper left-hand contact 374 (7), conductor 236, inner right-hand armature of relay 250, and thence to ground over the conductor 237. Magnet 316 attracts its armature prepara-

tory to advancing the brushes 344 and 343 to their next position terminals. Relay 249 also completes a circuit from battery through the winding of the stepping relay 207, inner left-hand armature and contact 70 of relay 249, front contact and left-hand armature of relay 250 to the grounded conductor 237.

At the time the relay 412 operated, the impulse circuit including conductors 244, 75 and 245 was extended by way of the left-hand armatures and back contacts of relay 448 to the windings of the relay 419 at the office selector switch. Relay 419 therefore becomes energized in series with the stepping relay 207 at the sender. Relay 419, 80 on attracting its armatures, completed a circuit from battery through the winding of slow to release relay 420, contact and right-hand armature of relay 419 to the grounded test terminal 418. Relay 420 becomes energized and locks in a circuit from battery through its winding and right-hand armature and contact to the grounded test terminal 418. When, therefore, the stepping relay 207 first attracts its armature to open the impulse circuit, relay 419 releases its armatures and a circuit is established from ground through the outer right-hand armature and contact of relay 419, left-hand armature and front contact of relay 420, winding of slow-to-release relay 421, winding of stepping magnet 422 to battery and ground. The primary stepping magnet 422 operates 95 to advance the brushes 427, 428, and 429 100 opposite the first level of terminals. Relay 421, which also energizes, completes a circuit as follows after the first primary step of the brush shaft: battery, through the winding of relay 425, lower springs of the off normal contact 426, armature and front contact of relay 421 to the grounded test terminal 418. Relay 425 becomes energized and closes a locking circuit for itself from battery through the winding of said relay, 110 lower springs of contact 426, armature and contact of the secondary stepping magnet 424, contact and outer armature of relay 425 to ground at the contact and outer right-hand armature of relay 448. When relay 249 and consequently relay 207 become deenergized, the circuit of relay 419 is completed, which operates to sever the energizing circuit of the stepping magnet 422. This magnet becomes deenergized and releases its armatures in readiness to advance the brushes through another step. For each 115 succeeding closure of the interrupter 376 the register 317 is advanced through one position and the office selector switch is operated to move its brushes opposite the next level. After the impulses have all been sent and the register 317 reaches its normal position the brush 343 engages an open terminal. Consequently, relays 252, 251 and 250 re- 120 125 130

lease their armatures. In the manner above described, relay 252 causes the time measuring switch to commence rotating and also opens the holding circuit of the stepping magnet 372, whereby the sender control switch moves out of position 7 and into position 8.

While the time measuring switch is passing through its cycle, relay 207 and relay 10 419 remain permanently energized. Consequently, relay 421 deenergizes after an interval and a circuit is established from battery through the inner armature and contact of relay 425, winding of the secondary stepping magnet 424, normal contacts of relay 421 to the grounded test terminal 418. Stepping magnet 424 energizes and advances the brushes 427, 428, and 429 into engagement with the first set of terminals in the chosen 15 group. The energization of magnet 424 causes the opening of the circuit of relay 425. Relay 425 releases its armatures and in turn opens the operating circuit of magnet 424. If at the time magnet 424 becomes 20 deenergized, the first trunk in the group is busy, a ground potential exists on terminal 432 thereof and a circuit is closed for the reenergization of relay 425. This circuit may be traced from battery through the 25 winding of said relay, lower springs of off normal contact 426, armature and contact of magnet 424, back contact and inner right-hand armature of relay 428, test brush 429 to the grounded test terminal 432. Relay 30 448, it will be observed, is included in parallel with this circuit. Relay 448, however, does not energize so long as it is shunted 35 out by direct connections to ground at the busy test terminals 432. Relay 425, on energizing completes a circuit for the stepping 40 magnet 424, which again operates to advance the brushes to the next set of terminals. This procedure continues until an idle trunk is located, at which time the relay 448 45 is included directly in series with relay 425. Relay 448 becomes energized but due to the high resistance thereof, relay 425 remains inert. Relay 448, at its left-hand armatures, opens the energizing circuit of relay 419. 50 Relay 448, at its front contact and inner right-hand armature, extends the grounded test conductor through to the test brush 429 and test terminal 432 to render the selected trunk busy to other selector switches. The 55 impulse circuit is now extended over the left-hand armatures and front contacts of relay 448, the left-hand armatures and back contacts of relay 440 to the windings of relay 433 and this relay becomes energized. 60 Relay 433 closes a circuit from battery through the winding of slow to release relay 434, contact and right-hand armature of relay 433 through the grounded test terminal 432. Relay 434 operates and locks up 65 in a circuit from battery through its wind-

ing and right-hand armature and contact, and thence to ground over the test terminal 432.

Following the operation of the office switch, it will be recalled that the sender 70 control switch advanced out of position 7 and into position 8. In this position the sender control switch waits until the operator has recorded the numerical designation on her keyboard. Provided the numerical keys have already been operated and the registers corresponding thereto have been adjusted to their proper positions, a circuit is completed for advancing the sender control switch. This circuit may be traced 75 from ground through the right-hand armatures and contacts of relays 323, 319, 318, 314, and 313 in series, lower right-hand contact 382 (8), contact and armature and winding of stepping magnet 372 to battery and ground. Stepping magnet 372 interrupts its own circuit and advances the sender control switch 80 out of position 8 and into position 9. In position 9 of the sender control switch all the operated keys are restored to normal. 85 For this purpose the key release magnets 354, 355, 356, 357, 358, 359, 360, 361 and 362 each of which controls a row of keys, are provided for releasing the depressed keys. A circuit for energizing these magnets may 90 be traced from battery through said magnets in parallel and thence to ground over the upper contacts 397 closed in position 9. As soon as the depressed keys have been released 95 the hereinbefore traced circuits, through the successive stepping magnets of the registers, are opened and these magnets, together with the relays in series therewith, became deenergized. A circuit is now established 100 from ground through the left-hand armatures and contacts of relays 323, 319, 318, 314, 313, 309, 308, 304, and 303 in series, left-hand armature and contact of relay 215, lower-right hand contact 373 (9), contact 105 and armature and winding of magnet 372 110 to battery and ground. Magnet 372 operates to advance the sender control switch out of position 9 and into position 10. With the sender control switch in position 115 10 the next idle register sender is allotted for use by the operator. The stepping magnet 210 of the allotter switch is energized in a circuit from battery through the winding and contact and armature of said magnet, right-hand contact 211 (1), lower right-hand contact 364 (10) to ground. Magnet 210 energizes and advances the allotter switch to its next stopping position, namely 120 position 4. In case the next register sender in order is idle at this time, relay 208 is inoperative and the allotter switch is immediately advanced into position 5 by means of a circuit from battery through the winding and armature and contact of magnet 210, left-hand contact 211 (4), to ground at the 125 130

back contact and outer armature of relay 208. In this position the next register sender is assigned for use and the incoming start wire 241 is extended over the lower right-hand contact 212, closed in position 5, to a conductor corresponding to conductor 242, which serves to advance the sender control switch of the allotted register sender out of position 1 when another call is answered at the operator's position. In a similar manner, after that register sender has been used, the allotter switch is advanced out of position 5 and into position 8 and then into position 9 where it allots the third register sender unit. Should all three of the register senders be busy simultaneously, a circuit is completed from battery through the winding of relay 208, contact 209, closed in either positions 4, 8, or 12, conductor 222, thence in series over two different contacts similar to the contact 370 and contact 297 to ground. The contact 370, which is shown in dotted lines, is individual to one of the other sender units not shown. For the third sender unit there will be provided another contact similar to the contact 370. Under these conditions the relay 208 is energized and the allotter switch is prevented from advancing into either of its allotting positions. Relay 208 also places a ground potential on each of the conductors 220 and 221, which results in the energization of all the key release magnets. Therefore, the operator is unable to record a designation on her keyboard until a register sender has become idle and is allotted for use.

With the sender control switch in position 10 a circuit is closed for relay 252 as soon as the time measure switch reaches its normal position, from battery through the winding of said relay, contact 248, brush 247, conductor 237, upper left-hand contact 385 (10), brush 345 to ground. Relay 252, in the manner explained, closes a locking circuit for magnet 246 and also for magnet 372. The first energization and deenergization of relay 249 result, as explained, in the operation of relays 251 and 250. On the next attraction of the armatures of relay 249, a circuit is closed from battery through the winding of magnet 321 of the first numerical register 322, lower left-hand contact 384 (10), conductor 236, inner right-hand armature and contact of relay 249, contact and right-hand armature of relay 250, and thence to the grounded conductor 237. Magnet 321 becomes energized and prepares to advance its brushes 345 and 346 forward one step. Relay 249 also completes the above traced circuit for the stepping relay 207. When relay 207 operates it opens the impulse circuit to permit relay 433 at the selector switch to release. Relay 433 establishes a circuit from ground through the outer right-hand armature and contact of

relay 440, left-hand armature and contact of relay 433, left-hand armature and front contact of relay 434, winding of slow-to-release relay 435, winding of the primary stepping magnet 436 to battery and ground. The magnet 436 energizes and moves the brushes 441, 442, and 443 one step forward into operative relation with the first level of terminals. When the brush shaft has taken its first step the off normal contact 447 is released and a circuit is closed from battery through the winding of relay 439, lower springs of contact 447, armature and front contact of relay 435 to the grounded test terminal 432. Relay 439 attracts its armatures and locks up in a circuit from battery through the winding of said relay, lower springs of contact 447, armature and contact of the secondary stepping magnet 438, contact and outer armature of relay 439 to ground at the contact and outer right-hand armature of relay 440. The interrupter 376, on opening, releases the relay 249, which in turn releases the relay 207 and relay 433 thereby becomes energized. The circuit of magnet 436 is now opened and its armatures are withdrawn to make ready for advancing the brush shaft another step. At each following operation of relay 249 the register 322 is stepped forward and the brush shaft of the selector switch is moved into operative relation with another level of terminals. When the register brush 345 finally reaches its normal position, ground is removed from conductor 237 and relays 252, 251 and 250 retract their armatures. Relay 252 permits the release of magnets 246 and 372. Consequently, the time measure switch starts out to complete another cycle while the sender control switch advances from position 10 and into position 11.

During the travel of the time measure switch through its cycle, relay 432 at the selector switch remains permanently energized and after an interval the slow to release relay 435 retracts its armature. A circuit is thereupon completed from battery through the inner armature and contact of relay 439, winding of magnet 438, closed contacts of relay 435 to the grounded test terminal 432. The secondary stepping magnet 438 moves the brushes into engagement with the first set of terminals in the selected level. Magnet 438 also severs the holding circuit of relay 439 which becomes deenergized and in turn opens the circuit of magnet 438. In the manner already explained, the relay 439 is again energized in case the test brush 443 engages a busy test terminal 446 and the stepping magnet 438 operates to advance the brushes on to the next set of terminals. This automatic trunk hunting operation continues until an idle trunk is found, at which time relay 439 remains energized and the relay 440 becomes operated

in series with relay 439. Relay 440, at its left-hand armatures, opens the circuit of relay 433 and at its inner right-hand armature extends the grounded third conductor 5 through to the test brush 443 and test terminal 446. The impulse circuit is thereupon extended to the next selector switch over the left-hand armatures and front contacts of relay 440, left-hand armatures and 10 back contacts of relay 507, and the windings of relay 500. Relay 500 becomes operated in the impulse circuit and attracts its armature. A circuit is then closed from battery through the winding of the slow-to-release 15 relay 501, contact and right-hand armature of relay 500 to the grounded test terminal 446. Relay 501 energizes and locks up in a circuit from battery through its winding and right-hand armature and contact, and 20 thence to ground, as described.

The time measure switch 240, on returning to its normal position, establishes once more the circuit for relay 252, which now leads by way of conductor 237, upper right-hand contact 385 (11) to ground over brush 347 of register 327. Relay 252 closes the holding circuits for magnets 246 and 372. The energization of relay 249 now completes a circuit for relay 251 which extends, as explained, over the grounded conductor 237, and thereafter the deenergization of relay 249 permits relay 250 to energize and lock up in series with relay 251. The next time relay 249 operates it extends the grounded 30 conductor 237 over its contact and inner left-hand armature to the winding of relay 207, and also over its contact and inner right-hand armature, conductor 236, lower right-hand contact 384 (11), winding of 35 stepping magnet 326 to battery and ground. The magnet 326 operates and relay 207 attracts its armature to open the impulse circuit. When the impulse circuit is opened relay 500 at the selector switch becomes de- 40 energized and completes a circuit from ground through the outer right-hand armature and contact of relay 507, left-hand armature and contact of relay 500, left-hand armature and front contact of relay 501, winding 45 of the slow to release relay 502, winding of the primary stepping magnet 503 to battery and ground. Magnet 503 and relay 502 operate in this circuit. Magnet 503 moves the brushes 509, 510, and 511 of the selector 50 switch into operative relation with the first group of terminals in the terminal bank. Relay 502 closes a circuit as soon as the off normal contact 508 is released at the first step of the brush shaft. This circuit may be 55 traced from battery through the winding of relay 506, lower springs of contact 508, armature and front contact of relay 502 to the grounded test terminal 446. Relay 506 actuates and locks up in a circuit from battery 60 through the winding of said relay, lower springs of off normal contact 508, armature and contact of stepping magnet 505, contact and outer armature of relay 506, contact and outer right-hand armature of relay 507 to ground. The next opening of interrupter 70 376 permits the release of relay 249, and consequently the deenergization of the stepping relay 207 and the stepping magnet 326. Magnet 326, on deenergizing, releases the 75 brushes 347 and 348 to their next position terminals. Relay 207 closes the impulse circuit and relay 500 energizing in response thereto opens the operating circuit including relay 502 and magnet 503. Stepping magnet 503 deenergizes but relay 502, being 80 slow-to-release in character, remains operated during the transmission of impulses. For each succeeding operation of relay 249 in response to the closure and opening of interrupter 376, the stepping magnet 326 is 85 energized and deenergized to advance the register brushes while stepping relay 207 operates to control the circuit of relay 500. In response to the operation of relay 500, stepping magnet 503 advances the brushes 90 of selector switch from position to position. As the register reaches its normal position, brush 347 disengages the grounded terminals and relays 252, 251, and 250 become deenergized. Relay 252 opens the holding circuit 95 of the magnet 246 so that the time measure switch commences to operate under the control of interrupter 376 to complete a rotation. The stepping magnet 372, on having its energizing circuit opened, releases to advance the sender control switch into position 100 12.

During the time the switch 240 is completing its cycle the relay 500 remains energized. After the necessary interval relay 502 releases its armature and a circuit is established from battery through the inner armature and contact of relay 506, winding of 105 the stepping magnet 505, closed contacts of relay 502 to the grounded test terminal 446. Stepping magnet 505 operates to advance the brushes 509, 510, and 511 into engagement with the terminals of the first trunk in 110 the selected group. Magnet 505 also opens the circuit of relay 506 which becomes deenergized and in turn opens the circuit of said magnet. If the first trunk in the group is busy its test terminal 514 will be identified by the presence of a ground potential and relay 506 becomes energized in a circuit 115 including the lower springs of contact 508, armature and contact of magnet 505, back contact and inner right-hand armature of relay 507, brush 511 to the grounded terminal 514. The relay 506 again prepares a circuit for the stepping magnet 505 which operates to advance the brushes onto the next set of terminals. When the first idle trunk is encountered, relay 506 remains deenergized 120 and the relay 507 is now operated since the 130

previously maintained shunt around its winding has been removed. Relay 507, at its left-hand armatures and contacts, opens the circuit of relay 500 which releases its armatures. Relay 507, at its inner right-hand armature and front contact, extends the grounded third conductor through to the test terminal 514 leading to the connector switch. Hence, the selected trunk is held busy to other group selector switches. Relay 507 also completes the impulse circuit for controlling the connector switch. This circuit may be traced from battery through the right-hand winding of relay 515, contact and outermost left-hand armature of relay 517, terminal 513, brush 510, front contact and inner left-hand armature of relay 507, thence over the lower side of the line through the armature and contact of relay 207 at the 10 sender and returning over the upper side of the line to the outer left-hand armature and front contact of relay 507, brush 509, terminal 512, make before break contact at the outer left-hand armature of relay 518, 20 through the left-hand winding of relay 515 to battery and ground. Relay 515 becomes energized and closes a circuit from battery through the winding of relay 516, contact and inner right-hand armature of relay 515, 30 contact and middle left-hand armature of relay 517 to the grounded third conductor 541. Relay 516 operates and locks up in a circuit from battery through its winding and left hand armature and contact, contact and middle left-hand armature of relay 517 35 to the grounded conductor 541.

The connection has thus been extended to the connector switch and the impulse circuit prepared for controlling the tens and 40 units selective movements of this switch in accordance with the setting of the last two registers of the sender. When the time measure switch 240 again reaches its normal position, relay 252 becomes energized in a circuit as hereinbefore traced to the conductor 237, thence over the lower right-hand contact 385 (12) to ground at the brush 349 of 45 register 332. Relay 252, as explained, completes circuits for magnets 246 and 372. Relay 249 energizes in response to the interrupter 376 and relay 251 operates and later 50 relay 250 is energized in series therewith. At the first energization of relay 249, following the operation of relay 250, the grounded 55 conductor 237 is extended by way of the contact and inner right-hand armature of relay 249, conductor 236, lower right-hand contact 383 (12), winding of magnet 331 to battery and ground. Also the grounded conductor 237 is extended by way of the contact and inner left-hand armature of relay 249, winding of relay 207 to battery and ground. Magnet 336 becomes energized for the purpose hereinbefore explained and 60 relay 207 attracts its armature to open the im-

pulse circuit and cause the release of relay 515 at the connector switch. Relay 515, upon deenergizing, establishes a circuit from ground through the innermost left-hand armature and back contact of relay 517, outer right-hand armature and back contact of relay 515, inner right-hand armature and front contact of relay 516, normally closed contacts 542 and 543, winding of slow to release relay 534, winding of primary stepping magnet 522 to battery and ground. The stepping magnet 522 operates to advance the brushes 528, 529, and 530 into operative relation with the first group of terminals. Relay 534 also becomes energized in series with magnet 522. The next opening of interrupter 376 causes the deenergization of relay 207 and stepping magnet 331. Magnet 331 releases the brushes 349 and 350 to their next position terminals, and relay 207 recloses the energizing circuit of relay 515. Relay 515 opens the above traced circuit for relay 534 and magnet 522. Magnet 522 becomes deenergized but relay 534, being slow-to-release, does not retract its armatures. On the next opening of the impulse circuit, relay 515 becomes deenergized and a circuit is closed from ground through the innermost armature and back contact of relay 517, outer right-hand armature and back contact of relay 515, inner right-hand armature and front contact of relay 516, contacts 542 and 533, armature and front contact and winding of relay 534, winding of stepping magnet 522 to battery and ground. The contacts 542 and 543 were opened and contacts 542 and 533 were closed upon the first primary step of the brush shaft, these contacts being so arranged that the closure of the latter pair takes place prior to the opening of the first mentioned contacts. The stepping magnet 522 again operates to advance the brushes of the connector switch to another group of line terminals. After the register 332 has been completely restored to its normal position, during which time the brushes of the connector switch are advanced from one group of terminals to another, the brush 349 disengages the last grounded terminal and removes ground from the conductor 237. In response to the removal of this ground, relays 252, 251, and 250 retract their armatures. Again the time measure switch 240 commences to rotate and the sender control switch advances through another position, coming to rest in position 13. Following the completion of the impulse series, relay 515 remains energized and after an interval the slow-to-release relay 534 retracts its armature.

When the time measure switch 240 reaches its normal position relay 252 is energized once more in a circuit traceable by way of conductor 237, lower right-hand contact 386 (13) brush 351 of the units register 337

to ground. In the manner well understood, relays 250, 251, and 249 operate under the control of the interrupter 376 to establish and disestablish in succession the operating circuits of the stepping relay 207 and the stepping magnet 336 of the units register 337, and also to close holding circuits for the stepping magnets 246 and 372 of the time measure switch and sender control switch, respectively. For each impulse transmitted, relay 515 releases its armatures whereupon a circuit is closed from ground through the innermost left-hand armature and back contact of relay 517, outer right-hand armature and back contact of relay 515, inner right-hand armature and front contact of relay 516, contacts 542 and 533, armature and back contact of relay 534, winding of slow to release relay 525, winding of the secondary stepping magnet 524 to battery and ground. Relay 525 and magnet 524 operate in this circuit. Magnet 524 serves to advance the brushes 528, 529, and 530 from one set of terminals in the selected group to another. When the last units impulse has been transmitted, the register brush 351 disengages the grounded terminals and relays 252, 251, and 250 become deenergized to in turn release the stepping magnets 246 and 372. The time measure switch 240 commences to rotate in the manner hereinbefore described. No useful function, however, is accomplished by the time measure switch at this time since all selections have now been completed. The magnet 372, on deenergizing, releases the sender control switch out of position 13 and into position 14. The brushes of the last switch in the series have now been positioned on the terminals of the called subscriber's line 540, but before continuing with an explanation of the testing and ringing operations, a description will be given of the manner in which the register sender is released and restored to its normal condition.

Since no stations impulses are to be sent, the sender control switch should be immediately moved out of position 14. This is accomplished by means of a circuit from battery through the winding and armature and contact of stepping magnet 372, lower contact 366 (14), contact 217 (4) of the class switch to ground. Magnet 372 operates to advance the sender control switch into position 15. A circuit is now established from battery through the winding and armature and contact of magnet 372 to ground at the upper right-hand contact 382 (15+18). By means of this circuit the sender control switch is stepped from position 15 through position 18 and into its normal position 1.

When the sender control switch moves out of position 14 the locking circuit through magnet 200 and relay 201 is opened at the

right-hand contact 365. Magnet 200 is now energized in a circuit from battery through its winding and armature and contact to ground at brush 202 of the cord finder switch. The magnet 200 interrupts its own circuit and steps the brushes 203, 204, 205, and 206 from position to position until they are completely restored to normal. At this time the operating circuit of magnet 200 is opened at brush 202 and the cord finder switch comes to rest.

At the same time the holding circuit of magnet 200 and relay 201 was opened, the relay 127, included in said circuit, also became deenergized. Relay 127 completes a circuit from battery through resistance 128, inner right-hand armature and back contact of said relay, contact and inner left-hand armature of relay 111, front contact and middle armature of relay 107, front contact and outer right-hand armature of relay 106, winding of relay 118 to ground. Relay 118 energizes in this circuit and opens the circuit which up to this time has been maintaining the relays 110 and 109 energized. Relay 109, upon deenergizing, automatically disconnects the operator's telephone set from telephonic relation with the calling subscriber's line and extends the conductors of the calling line through to the left-hand windings of the repeating coil 139. Relay 110, on releasing its armatures, opens the holding circuits of relays 113 and 114. Relay 113 opens the locking circuit of relay 111 and this relay becomes deenergized. Relay 114, at its left-hand armature, opens the circuit of relay 117. Relay 114, at its innermost right-hand armature and front contact, opens the circuit through interrupter 121 which has been causing the lamp 123 to flash. The lamp 123 is now illuminated steadily in a circuit from battery through said lamp, resistance 126, outer right-hand armature and contact of relay 116, innermost right-hand armature and back contact of relay 114 to ground at the contact and outermost right-hand armature of relay 115. It will be noted that relay 115 becomes energized over conductor 403 at the time the offnormal contact 411 closed on the first step of the district selector switch. The lamp 123 by discontinuing its flashing signal and burning steadily indicates to the operator that all selections have been completed and the register sender disassociated from the cord circuit.

Returning now to the point where the connector switch is positioned on the terminals of the called subscriber's line in response to the transmission of the units series of impulses, a consideration will be given to the testing and signaling operations which follow automatically. Assuming the called subscriber's line 540 to be idle when units selection is completed, a circuit

- is established as follows as soon as relay 525 releases its armatures: battery, through the winding of the cut-off relay 527 of the called subscriber's line, test brush 530, left-hand armature and back contact of relay 525, contact and outermost left-hand armature of relay 526, left-hand winding of relay 517, front contact and outer right-hand armature of relay 515, back contact and 10 innermost left-hand armature of relay 517 to ground. The relay 517 energizes in this circuit. The innermost right-hand armature of relay 517 is adjusted to make its front contact slightly in advance of the opening 15 of the back contact and innermost left-hand armature of said relay. Consequently, before the above traced energizing circuit for the left-hand winding of relay 517 can be opened at its innermost left-hand armature 20 and back contact, the following circuit is closed to hold said relay energized: battery, through the right-hand winding and contact and innermost right-hand armature of relay 517 to ground over the conductor 541. 25 Relay 517 opens the holding circuit of relay 516 and this latter relay retracts its armatures. Relay 517 furthermore completes the ringing circuit over which signaling current is applied to the called subscriber's line. 30 The ringing circuit may be traced from the source of current 520 to the left-hand winding of relay 518, back contact and inner left-hand armature of said relay, contact and outermost right-hand armature of relay 517, 35 outer right-hand armature and contact of relay 526, brush 529, thence over the loop of the called subscriber's line, brush 528, back contact and inner right-hand armature of relay 526 and middle armature and contact 40 of relay 527, outer left-hand armature and back contact of relay 518 to ground. Relay 518 does not operate in the circuit traced due to the high resistance of the ringer magnet at the substation. 45 When the called subscriber answers by removing his receiver from the switch hook, the resistance of the ringer magnet is excluded and sufficient current flows through the left-hand winding of relay 518 to cause 50 the actuation thereof. Relay 518 immediately locks up in a circuit from battery through its right-hand winding and right-hand armature and contact, normal contact of relay 519, terminal 512, brush 509, front contact 55 and outer left-hand armature of relay 507, thence over the front contacts and outer left-hand armatures of the relays 440, 448, and 512 at the preceding group selector switches, conductor 400, outer left-hand armature and back contact of relay 127, normal contact of the relay 110, upper right-hand winding of repeating coil 139 to ground. The relay 518 being energized and the called subscriber's receiver being off the switch hook, 60 a closed circuit is established through the

left-hand armatures and front contacts of relay 518 over the talking conductors through to the right-hand windings of repeating coil 139. The relay 521 being included in this closed circuit energizes and 70 completes the energizing circuit for relay 519. Relay 519 at its armature and make-before-break contact provides a substitute holding circuit for the right-hand winding of relay 518 through the grounded conductor 541 independent of the first energizing circuit which leads over the upper talking conductor to ground at the repeating coil 139. 75

Relay 131 in the operator's cord circuit 80 also energizes in series with relay 521 and the called subscriber's substation. This relay completes a circuit from battery through its armature and contact, normal contacts at the inner left-hand armature of relay 116, 85 winding of relay 116, innermost right-hand armature and contact of relay 115 to ground. Relay 116 immediately operates and locks up in a circuit from battery through its inner left-hand armature and front contact and winding to ground at the innermost right-hand armature of relay 115. Relay 116 completes a circuit from battery through the lamp 122, resistance 125 to ground at the inner right-hand armature and front contact 90 of relay 117. The lamp 122, however, does not illuminate since it is shunted out by a direct circuit from battery to ground which may be traced as follows: battery, through the armature and contact of relay 131, contact and outer left-hand armature of relay 116, resistances 124 and 125, inner right-hand armature and front contact of relay 116 to ground. Relay 116, on energizing, also opens the above traced circuit through the lamp 100 123. The retirement of the signal 123 advises the operator that the called subscriber has responded. A complete talking circuit 105 is now established and the calling and called subscribers may converse with each other. 110

At the end of the conversation the calling and called subscribers by replacing their receivers on the switch hooks cause the deenergization of the supervisory relays 129 and 131 in the operator's cord circuit. Relay 129 115 removes the shunt from around the lamp 108 and this lamp becomes illuminated to notify the operator that the calling party has hung up his receiver. Similarly, the relay 131 opens the shunt around lamp 122 which 120 lights to advise the operator that the called subscriber has hung up his receiver. In response to these signals the operator seizes the plug 105 and withdraws it from the jack of the calling line. The removal of the plug 125 from the jack opens the circuit of relay 106 which deenergizes and in turn opens the holding circuit for relay 107, permitting this latter relay to release its armatures. Relay 107, at its outermost armature and front 130

contact, removes ground potential from the conductor 402. This opens the parallel circuits of relays 412, 448, 440, and 507 which have been holding these relays energized. 5 The resulting deenergization of relay 412 causes the closure of a circuit from battery through the winding of release magnet 408, middle springs of off normal contact 411, back contact and armature of relay 405, back 10 contact and armature of relay 404 to ground at the contact and outer right-hand armature of relay 412. The release magnet 408 operates in this circuit and restores the brush shaft of the district selector to its normal 15 position. In the restored position of the brush shaft the off normal contact 411 opens its several springs and the release magnet 408 becomes deenergized. In a manner identical to that described release circuits are also 20 closed for the release magnets 423, 437, and 504 of the three succeeding switches and these switches are restored to their normal positions. It will also be noted that the removal of the ground potential from conductor 25 402 also permitted the release of relays 420, 434, and 501.

When the called subscriber hung up his receiver relay 521 became deenergized and permitted the release of relay 519. Since at 30 this time the upper talking conductor is opened by reason of the preceding switches having been released, the release of relay 519 does not reclose the original holding circuit of the relay 518. When ground potential 35 is removed from the conductor 541 due to the deenergization of relay 107 and the release of the intermediate switches, the holding circuit of relay 517 is opened and this relay retracts its armatures to establish 40 the release circuit. The latter circuit may be traced from battery through the winding of release magnet 523, springs 544 and 545, back contact and inner right-hand armature of relay 516, back contact and outer 45 right-hand armature of relay 515 to ground at the back contact and the innermost left-hand armature of relay 517. It will be observed 50 that relay 516 immediately deenergizes as soon as ground potential is removed from conductor 541. Release magnet 523 operates in the well-known manner to return the brush shaft of the connector switch to its normal position.

The occasion frequently arises that the operator 55 wishes to recall the called subscriber after he has hung up his receiver and prior to the time that the train of switches are released. The necessity of such an act on the part of the operator usually results from a request by the calling subscriber that he 60 again be placed in conversational connection with the called line. He attracts the operator's attention in the usual manner by moving the switch hook to cause the intermittent illumination of the supervisory

lamp 108. Responding to this signal the operator depresses her listening-in key 140, the plug 105 still remaining in the jack of the calling line. The key 140 closes a circuit from battery through the windings of relays 70 109 and 110 in parallel, through the contacts of said key, front contact and outer right-hand armature of relay 108 to ground at the contact and armature of relay 117. The operation of relay 109 again places the operator's telephone set 130 in talking relation with the calling subscriber's line, while relays 109 and 110 become locked up through the key 119, as hereinbefore explained. The called subscriber having hung up his receiver prior to this time, relay 521 is deenergized and relay 518 is now held energized in a circuit through its right-hand winding and right-hand armature and contact and the make-before-break contact of relay 519 80 85 to ground as previously traced over the upper talking conductor, through the normal contact at the inner right-hand armature of relay 110, upper right-hand winding of repeating coil 139 to ground. When relay 90 95 110 becomes energized in response to the operation of the operator's listening-in key 140, the circuit for relay 518 is modified to the extent that it now leads over the upper talking conductor 400, contact and outer 100 right-hand armature of relay 110, key 120, inner right-hand armature and front contact of relay 110, through the upper right-hand winding of repeating coil 139 to ground. This circuit is thus made dependent upon 105 the condition of the operator's key 120. To ringer the called subscriber's line the operator merely depresses the key 120 to temporarily open the above traced circuit for relay 518. Relay 518 becomes deenergized 110 and at its left-hand armatures completes the ringing circuit for applying ringing current to the called subscriber's line. When the called subscriber answers, the circuits are converted in the manner already explained 115 and further conversation may take place between the subscribers.

The operator having succeeded in recalling the called subscriber now retires from the connection by depressing her listening-out key 119. The operation of this key opens the locking circuits of relays 110 and 109 and the resultant operations take place as described.

It will next be considered that the called subscriber's line 540 is busy at the time the brushes of the connector switch are set on the terminals thereof. The line being busy, a ground potential exists on the test terminal and the following circuit is immediately 120 125 closed as soon as the last impulse has been transmitted: battery, through the winding of relay 516, make before break contact and left-hand armature of relay 525, which relay remains energized for an interval following 130

the impulse series, test brush 530 to the grounded test terminal of the called subscriber's line. The circuit for providing this ground potential on the test terminal of an engaged line leads from the innermost left-hand armature and front contact of relay 517, outermost left-hand armature and contact of relay 526, back contact and left-hand armature of relay 515, and thence to said test terminal. The above traced circuit being closed for relay 526, this relay operates and locks up in the following circuit as soon as the slow-to-release relay 525 retracts its armatures: battery, through the winding of relay 526, normal contacts of relay 525, contact and middle left-hand armature of relay 526 to the grounded conductor 541. Relay 526, at its right-hand armatures, opens the talking conductors to prevent the application of ringing current to the called subscriber's line. Relay 526 moreover completes a circuit from ground through the secondary winding of the tone coil 531, interrupter 532, contact and right-hand armature of relay 525, contact and innermost left-hand armature of relay 526, outer right-hand armature and front contact of relay 516, right-hand winding of relay 517 to battery and ground. The first closure of the interrupter 532 causes the energization of relay 517 which locks up over its innermost right-hand armature to the grounded conductor 541. Relay 517 opens the holding circuit for relay 516 which immediately releases its armatures. On succeeding closures of the interrupter 532 a circuit is completed through the tone coil and interrupter, contact and right-hand armature of relay 525, contact and innermost left-hand armature of relay 526, outer right-hand armature and back contact of relay 516, right-hand winding of relay 515 to battery and ground. The current in this circuit induces a current in the left-hand winding of relay 515 which is transmitted over the talking conductors to the windings of the repeating coil 139, and thence to the receiver at the calling subscriber's station. A characteristic sound in the calling subscriber's receiver notifies him that the called party is busy. The calling subscriber on abandoning the call causes the release of the supervisory relay 129 and the operator in response thereto takes down the connection in the manner previously discussed.

The operator's telephone set may be connected in talking relation to a particular cord circuit either by reason of the fact that the register sender has not yet reached the proper stage for automatically disassociating said telephone set, or because the operator has reassociated her telephone set with the cord circuit for supervisory purposes. In either of these cases, it is possible for her

to automatically disconnect her head set from the first cord circuit and to associate the same with a second cord circuit by the act of inserting the plug of said second cord circuit in the jack of another calling line. Assume that another line similar to line 100 makes a call while the operator's telephone set is connected to one of the cords at her position. The operator by seizing the plug 105 of another cord circuit at her position (not shown), and inserting it in the jack 104 of the second calling line, causes as has been seen, the operation of relay 106 belonging to the second cord circuit. The operation of relay 106 closes the series parallel circuit through the windings of relays 109 and 110 of the second cord circuit, through the back contact and middle armature of relay 107 of the second cord circuit, front contact and outer right-hand armature of relay 106 and thence to ground through the winding of relay 118 shown in the drawing. It may be noted at this time that relays 117 and 118 are common to all the cord circuits at an operator's position. The relay 117, it will be recalled, is energized since relay 114 is being maintained energized by the relay 110 of the first cord circuit. Therefore, the series parallel circuit above traced for relays 109 and 110 includes the winding of the common relay 118 and does not lead directly to ground, through the contact and armature of relay 117, this relay being energized. The resistance of relay 118 is such that it does not permit the operation of relays 109 and 110 at the second cord circuit. Consequently, the operator's telephone set is not immediately connected to said circuit. Relay 118, however, does attract its armature and in so doing opens the holding circuit of relays 109 and 110 belonging to the first cord circuit. Relay 109 disassociates the operator's telephone set therefrom, while relay 110 permits the release of relays 113 and 114. The release of relay 114 opens the holding circuit of relay 117 and this relay on releasing its armature shunts out the winding of relay 118, thereby permitting the operation of relays 109 and 110 individual to the cord circuit which the operator has taken for use in answering the second calling line. The relay 109 of this circuit upon operating connects the operator's telephone set to the cord and, therefore, in talking relation with the second calling subscriber's line. Thus, it will be seen that the simple act of responding to a second call serves to automatically disconnect the operator's talking set from any cord circuit with which it may be in talking relation and to associate the same with the new cord taken for use.

In a similar manner, the operation of the listening key 140 individual to any cord cir-

cuit at the operator's position serves to automatically disconnect the operator's telephone set from the particular cord circuit to which it may happen to be connected at the time and to associate said telephone set with the cord circuit to which the depressed key 140 belongs.

What is claimed is:

1. In a telephone system, subscribers' lines, an operator's position having connecting circuits thereat, a telephone set, selective switches for extending said lines, a register sender for controlling said switches, a relay individual to each connecting circuit for connecting said circuits to the telephone set, means controlled by the register sender for rendering said relays effective to disconnect the connecting circuits from said telephone set, a common relay having its winding in circuit with said individual relays, and means controlled by said common relay for rendering said individual relays effective to disconnect the connecting circuits from the telephone set.
2. In a telephone system, subscribers' lines, an operator's position, cord circuits and selective switches for extending the lines, a register sender for governing the selective switches, a telephone set, a relay individual to each cord, means when a cord is taken in use for operating the individual relay to connect such cord to said telephone set, means controlled by said sender for rendering the individual relay effective to disconnect the cord from the telephone set, a common relay having its winding in circuit with a number of the individual relays and operable when another cord is taken in use simultaneously, and means controlled by said common relay for rendering the first mentioned individual relay effective to disconnect the corresponding cord from the telephone set.
3. In a telephone system, subscribers' lines, cord circuits and selective switches for extending the lines, a register sender for governing the selective switches, a telephone set, a relay individual to each cord, means when a first cord is taken in use for operating the individual relay to connect such cord to the telephone set, means controlled by the sender after it has completed its control of the selective switches for rendering the individual relay effective to disconnect the first cord from the telephone set, a relay common to said cords and having its winding in circuit with each of the individual relays, said common relay being operable

when a second cord is taken in use simultaneously with the first cord, and means controlled by the common relay for rendering the relay individual to the first cord effective to disconnect such cord from the telephone set.

4. In a telephone system, subscribers' lines, an operator's position, cord circuits and selective switches for extending the lines, a register sender for controlling the selective movement of the switches, an operator's telephone set, a relay individual to each cord circuit, means operative when a first cord is taken in use for actuating the individual relay to connect such cord with the telephone set, means controlled by said sender for rendering the individual relay effective to disconnect the cord from the telephone set, a relay common to said cords having its winding in circuit with a number of the individual relays, said common relay being operative when a second cord is taken in use during the use of the first cord, and means controlled by said common relay for rendering the relay individual to the first cord effective to disconnect such cord from the telephone set and for rendering effective the relay individual to the second cord to connect such second cord to the telephone set.

5. In a telephone system, subscribers' lines, an operator's position, cord circuits and selective switches for extending the lines, a register sender for governing the operation of said switches, a telephone set, a relay individual to each cord, means when a cord is taken in use for operating the individual relay to connect such cord to said telephone set, means controlled by said sender for rendering the individual relay effective to disconnect the cord from the telephone set, a common marginal relay having its winding in circuit with a number of individual relays, said marginal relay being effective when the individual relay of a second cord is placed in circuit therewith during the time a first cord is in use for rendering the relay individual to the first cord effective to disconnect such cord from the telephone set and for subsequently rendering the relay individual to said second cord effective to connect said second cord to the telephone set.

In witness whereof, I hereunto subscribe my name this 15th day of December, A. D. 1920.

WALTER P. ALBERT.
